UNITED STATES PATENT OFFICE.

GUY CROSIER ADAMS, OF LAUNCESTON, TASMANIA, AUSTRALIA.

COIN-CONTROLLED MACHINE FOR PUBLIC TELEPHONES.

1,257,062.

Specification of Letters Patent. Patented Feb. 19, 1918.

Application filed May 12, 1917. Serial No. 168,324.

To all whom it may concern:

Be it known that GUY CROSIER ADAMS, a subject of the King of Great Britain, residing at Launceston, Tasmania, Australia, 5 State of Tasmania, has invented certain new and useful Improvements Relating to Coin-Controlled Machines for Public Telephones, of which the following is a specification.

This invention has reference to coin-in-slot mechanism, that is attached to public telephones, and has for its object to establish signals between the exchange and the person desiring to use a line by means of a coin or coins which he has inserted in the 5 mechanism as payment for the call.

Means are provided in effecting the purpose of the invention whereby coins of varying values may be employed and signals sent in accordance with the value of the coin 0 used. A further object of the invention is the provision of means for returning wrongly inserted coins to the person operating the device; for locking the mechanism and for preventing more than one set of 5 mechanism from operating at one time.

In the accompanying drawings:

Figure 1 shows the invention in side sectional elevation.

Fig. 2 is a plan of same.

Fig. 3 is a detail of the plunger locking means.

Fig. 4 illustrates the plunger in different positions, and also the details of the release mechanism therefor.

Fig. 5 shows the make and break device and means of operating same.

Fig. 6 is a further detail of means for preventing a plunger being used twice with one coin.

Fig. 7 shows a device for actuating such means, and

Fig. 8 is a further detail of same.

The container 9 has a number of slots 10 that are made in varying sizes to accommodate coins of the respective values of say, one penny, threepence, sixpence, and one shilling. The slots are immediately over plungers 11 in which are like slots or openings to receive the coins from the slots and 10 support the same vertically in the plungers.

Immediately below the openings in the plungers are relatively smaller slots as 12 through which will fall coins or substitutes for the same, not of the same diameter as 55 the coin to be used in a particular slot.

Such will fall through into the chute indi-

cated by the dotted lines, and will be recoverable at the point 13.

Each plunger and slot is marked according to its coin value and each plunger passes 60 at its inner end through a plate 14 having a longitudinal slot 15 in which is a stud 16. The inner ends of the plungers are formed or tapered in various degrees, no two being alike, so that when one plunger is forced 65 through the opening in the plate to the square part of same (indicated at the right in Fig. 3) the plate 14 will have imparted to it a slight lateral movement upon the stud 16 which will be sufficient to cause it to 70 bite the other plungers which will thereby be locked until the operated plunger is returned to its normal position. The normal positions of the plungers relatively to the plate 14 are shown in Fig. 3 of the drawings, the part of each plunger that is in the plate opening being indicated by the cross hatching, while the rectangles indicate cross sections of the plungers at points in their main parts.

When a coin is dropped in a slot it will fall into the plunger slot, and rest on the chute slot 12 until the plunger is pressed inward. Pivotaly mounted on the covering immediately over each plunger is a recessed 80 plate 17, formed substantially as indicated, and receiving in its recess a pin 18 on the plunger which limits the forward movement of the latter. But when a coin is in the plunger and it is pushed into the machine, 85 the top of the coin, as it is carried along by the plunger, impinges against the edge of the plate 17 and causes it to be swung out of the way of the advancing pin 18, which 90 clears the plate. A further pin 19 on the 95 plunger to the rear of pin 18 will eventually contact with the rear edge of the plate and keep it open until the coin passes free, (see Fig. 4). The coin will then fall through the slot 20 into the till. The plate 17 is returned to its normal position by the spring 21, and the plungers by other conveniently placed tension springs.

The plunger plate 14 is mounted on the bridge 22 through which the ends of the 100 plungers pass to make contact with the levers 23 which are on the spindle 24, whereon are also the ratchet wheels 25, and the free wheel 26 and drum 30. The distance of the levers 23 from the plungers can be regulated by the set screws 27, the throw of the 105 levers being greatest when operating with 110

the highest coin value. Suitable tension springs on the bridge keep the levers in contact with the set screws, and a pawl 28 on each lever engages with the teeth of wheel 5 25 and causes same to be turned one, two, three, or four teeth as a lever is rocked by impact from a corresponding plunger.

If a lever be operated from a penny plunger the throw of the ratchet 25 will be 10 equal to one tooth; if from the threepenny plunger, two teeth; with the sixpenny plunger, three teeth, and by the shilling plunger, four teeth.

Attached to the spindle 24 and drum 30 15 respectively is a coiled flat spring 29 housed in the drum which is wound when a wheel 25 is turned. The spring thus imparts movement to the drum on which is a toothed wheel 31 on which the contact maker 32 20 rides, which contact maker communicates the signals to the exchange through a buzzer 33 as the drum rotates. A fan governor 34 may be operated through the gearing 35 from the wheel 26 to regulate the speed of 25 the drum. A plate 33^a closes the drum 30 and is provided with a recess 34^a, tapered at one side to accommodate a like shaped boss 35^a on a flat spring 36 mounted on the drum. The plate 33^a is attached to the spindle 24 and when the spindle is turned 30 through one of the ratchets the boss is forced out of the recess as indicated in Fig. 8 and forces outward the floating plate 37. This plate is loosely mounted on the machine 35 casing (Fig. 2) and has at its lower end an inclining projection 38 (Fig. 7) on which rests the end of a lever 39 pivotally mounted at the base of the bridge 22. The forward end of this lever is on a transverse 40 spindle 40 on which are attached stop plates 41 having notched ends for engaging pins 42 that are on each plunger.

When a ratchet is operated one, two, three or four teeth as the case may be, the plate 37 45 is forced outward and the lever 39 that rests on its inclined foot 38 drops slightly. This movement is assisted by the spring 43 and permits the lever to be rocked and to slightly lift the transverse spindle 40 on 50 which are the stop plates 41; these will then engage the pins 42 on the plungers if a plunger is pushed in again before a cycle is complete. The mechanism thus prevents a plunger being operated more than once with one coin. Immediately the member 35^a is ejected 55 from the recess 34^a the spring 29 in the drum reacts to bring it back into the recess, into which it will be forced by the spring 36. When this takes place the plate 37 resumes 60 its normal position, the lever 39 is lifted and the stop plate 41 falls away from the pin 42.

In practice, if a call costing two pence is required, the caller will place two pennies in the proper slot and push in the plunger; 65 this will first lock the other plungers in the

plate 14 and then operate the lever to rotate a ratchet one tooth thereby transmitting one call to the exchange. Immediately the plunger returns to the normal position the second penny in the slot will fall into the plunger 7 and the operation will be repeated.

The machine is, for sake of convenience, designed to take British coinage, but it is evident that it may be adapted to work with coinages other than British. 7

Owing to the sizes of the coin slots varying and each being capable of receiving a different coin, the line can be quickly got by permission of the exchange obtained through the signaling means. The appliance will be attached in a convenient position on a public telephone with the necessary short directions for its use. 8

Having now described my invention what I claim as new and desire to secure by Letters Patent is:—

1. In machines of the kind indicated, a series of coin slots and a series of plungers for carrying coins and each associated with a slot, each plunger having a slot normally 9 below and in line with a coin slot, a movable recessed plate near a plunger and adapted to be swung aside when the plunger carrying a coin is pressed inward, a pin on the plunger in the recess of the plate, a second pin 9 behind the first on the plunger, means for discharging a coin after use, and means for returning the plate to its normal position.

2. In machines of the kind indicated having a series of associated slots and plungers, in combination, a spindle, ratchet wheels and rocking levers thereon, each lever being placed opposite a plunger end, a pawl on each lever for engaging a ratchet, set screws adapted to regulate the distance of each 1 lever from each plunger, and an electric contact maker controlled by said ratchets.

3. In machines of the kind indicated having a series of associated slots and plungers, in combination, a spindle, ratchet wheels 1 and rocking levers thereon, each lever being placed opposite a plunger end, a pawl on each lever for engaging a ratchet, set screws adapted to regulate the distance of each lever from each plunger, a drum loosely 1 mounted on the spindle, a coiled spring within the drum attached to the spindle at one end and to the drum at the other, a toothed wheel upon the drum and an electric contact breaker riding on the toothed 1 wheel.

4. In machines of the kind indicated, a ratchet spindle, a drum loosely mounted thereon, a coiled spring within the drum attached to the spindle at one end to the drum 1: at the other, a recessed lid for the drum held upon the drum spindle, a flat spring on the drum and a boss on the spring taking into the recessed lid, as and for the purposes set forth.

5. In machines of the kind indicated, a ratchet spindle, a drum loosely mounted thereon, a coiled spring within the drum attached to the spindle at one end and to the drum at the other, a recessed lid for the drum held upon the drum spindle, a flat spring on the drum, a boss on the spring taking into the recessed lid a plunger and means for preventing the plunger being used 10 more than once with each coin.
6. In machines of the kind indicated, means for avoiding a plunger being used more than once, with one coin, which consists of the combination of a ratchet spindle, 15 a drum loosely mounted thereon, a spring within the drum, and a recessed lid on the drum and rotating with the spindle, a floating plate having a foot adapted to be moved from and to the drum, a rocking lever resting on said foot, a transverse spindle attached to the lever, and stop plates on the spindle in combination with a plunger having a pin on its side to be engaged by the stop plates while a signal is being made.

In testimony whereof I affix my signature 25
in presence of two witnesses.

GUY CROSIER ADAMS.
